United States Patent Office

Des. 191,030
Patented Aug. 8, 1961

191,030

NOTEBOOK COVER

Seymour Mace Cole, 250 Mortimer Road, Glencoe, Ill.,
and Paul I. Dale, 808 La Crosse, Wilmette, Ill.

Filed Sept. 28, 1960, Ser. No. 62,297

Term of patent 14 years

(Cl. D6—2)

Fig. 1.

Fig. 2.

FIG. 2 is a bottom plan view thereof on slightly reduced scale; and

FIG. 3 is a sectional view thereof taken on the line 3—3 of FIG. 2.

We claim:

The ornamental design for a notebook cover, as shown.
